CLOCK

Andrew Weining, 1317 Lynn St., Erie, Pa. 16503

Filed Sept. 8, 1965, Ser. No. 86,910

Term of patent 14 years

(Cl. D42—7)

The figure is a front view of a clock embodying my new design.

The back is plain.

The right hand side is substantially identical in appearance to the left hand side.

This application is a continuation-in-part of my prior copending application, Serial No. D. 79,423, filed April 9, 1964 and now abandoned.

I claim:

The ornamental design for a clock, as shown and described.
